UNITED STATES PATENT OFFICE.

VOJTECH PUC, OF PRAGUE-VINOHRADY, BOHEMIA.

CROCHET NEEDLE.

1,415,472.

Specification of Letters Patent. Patented May 9, 1922.

Application filed August 1, 1919. Serial No. 314,764.

(GRANTED UNDER THE PROVISIONS OF THE ACT OF MARCH 3, 1921, 41 STAT. L., 1313.)

To all whom it may concern:

Be it known that I, VOJTECH PUC, a citizen of the Czechoslovak Republic, residing at Prague-Vinoohrady, in Bohemia, have 5 invented certain new and useful Improvements in Crochet Needles, (for which I have filed applications in Germany, filed Oct. 18, 1917, patented Aug. 23, 1918, No. 308,793; in Spain, filed Dec. 9, 1919, patented Mar. 10 15, 1921, No. 71,642; in France, filed Dec. 30, 1919, patented July 10, 1920, No. 507,966,) of which the following is a specification.

The object of this invention is to provide 15 a crochet needle of improved construction, made from a single piece of wire of uniform size and in such manner as to provide a handle and a finger rest suitably located.

In the accompanying drawings:—

20 Figure 1 is a perspective view of a preferred form of needle embodying my improvements.

Figure 2 is a view on an enlarged scale 25 illustrating more particularly the manner in which the end of the wire is held.

Figure 3 shows a section on the line 3—3 of Figure 1.

Figure 4 is a view of a modification in 30 which the shank of the needle, or that part forming the handle in Figure 1, is made shorter and inserted in a wooden handle.

Referring to Figures 1, 2, and 3, the handle 35 A and the working end B of the needle are made from a single piece of wire. The working end is formed with the usual hook b and the wire is bent at a to form the two members of the handle. The upper portion of the handle has a narrow loop x, while the lower portion has a wider loop y. The two 40 members of the handle are brought together at z and are then spread and curved to form a circular finger rest D. The free end of the bent wire is then brought close to the wire on the other side of the needle and 45 is held there by clamp E, preferably made of sheet metal and so formed as to lock the two sides of the needle together in the manner indicated, particularly in Figure 3, so that the two sides of the needle are rigidly 50 held in place and the clamp itself is prevented from slipping endwise on the needle owing to its particular shape and to the face that it holds the free end of the wire under tension.

In Figure 4 a modification is shown in 55 which the needle is made much shorter, providing merely a shank for the needle which is inserted in a socket in a suitable handle or hand piece F, from which it may be removed and the needle may be reversed so 60 that its hooked end will extend into a socket f formed in the handle. In each case, however, the working part of the needle and the finger piece, as well as the shank or handle A, are formed from a single piece of 65 wire. Needles of the form illustrated can be very easily made at smaller expense than the ordinary kind. The shape of the needle is most convenient and the finger rest is a desirable feature. 70

The needle, it will be observed, is made from a single piece of wire and a single piece of sheet metal. The wire is of substantially the same thickness throughout except at the extreme end where the hook 75 is located. It will be observed that the clamp E has a flat side which can readily receive a trade-mark and designations indicating the number and size of the needle. 70

I claim as my invention:—

1. A crochet needle formed from a single piece of wire, having a hooked working end and a handle formed by bending the wire upon itself to form a narrow loop and a wide loop, and a ring to provide a finger 85 rest, in combination with a clamp for holding the free end of the wire close to the inner portion of the working end of the needle.

2. A crochet needle formed from a single piece of wire, having a hooked working end 90 and a handle formed by bending the wire upon itself to form two handle members, and a finger rest in combination with a clamp made of sheet metal which embraces the inner portion of the working end of the 95 needle and the free end portion of the wire.

3. A crochet needle formed from a single piece of wire having a hooked working end and a handle formed by bending the wire upon itself to form a loop, and a ring to 100 provide a finger rest in combination with a clamp for holding the free end of the wire below the ring close to the inner portion of the working end of the handle.

In testimony whereof, I have hereunto 105 subscribed my name.

VOJTECH PUC.
